Atty.

UNITED STATES PATENT OFFICE.

MATHEW DILL, OF PIQUA, OHIO.

CAR-COUPING.

SPECIFICATION forming part of Letters Patent No. 334,355, dated January 12, 1886.

Application filed November 7, 1885. Serial No. 182,138. (No model.)

To all whom it may concern:

Be it known that I, MATHEW DILL, a citizen of the United States, residing at Piqua, in the county of Miami and State of Ohio, have 5 invented certain new and useful Improvements in Car-Couplings; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

This invention relates to car-couplings; and 15 it consists in the detailed construction and combination of the parts hereinafter fully described and claimed.

In the drawings, Figure 1 is a side view of 20 two couplings connected together, the positions of the coupling-hooks before engagement being indicated by dotted lines. Fig. 2 is a plan view of the same. Fig. 3 is a side view of one coupling provided with a special link engaging with a pin-and-socket coupling 25 as ordinarily used. Fig. 4 is a plan view of the same.

Similar letters of reference indicate corresponding parts in all the figures.

A is the coupling-socket, one of which is 30 attached to each end of each car by any suitable arrangement of draw-bar and springs; or it may be bolted to the car.

Each socket A is provided with a vertical hole, a, and a vertical slot, a'. A portion of 35 the top of the socket is cut away at one end of the hole a, leaving the bar a² of suitable form for the coupling-hook to catch over.

Horizontal holes a³ are formed in the socket on each side of the vertical slot a', and short 40 vertical slots a⁴ are formed at one end of the holes a³, so that the pivots of the coupling-hook may be inserted into the said holes.

B is the coupling-hook, provided with pivots b, trip b', and stop b².

C is a cover-plate, pivoted to the top of the 45 socket by the pin c, and provided with a slot, c', in which the coupling-hook works.

When the cars are approaching each other, 50 the coupling-hooks stand, as shown by the dotted lines in Fig. 1, with the stops b² resting upon the top of the cover-plates. When the cars meet, the trip b' of each hook strikes against the end of the socket on the opposite car, and each hook falls and catches over the 55 bar a² of the opposite socket.

In order to uncouple the cars, they must be pushed together. The hooks can then be raised, using the trip b' for handles.

The cover-plate keeps each hook or link from coming out of the horizontal holes in the 60 socket.

When it is desired to couple a car provided with a socket, A, to another car having a common pin-and-socket coupling, such as D, a special link, E, is used. The link E is open 65 at one end, and is provided with a pivot, e, and a hook, e'. The coupling-hook B is removed from the socket by turning the cover-plate on its pivot until the pivots b can pass out of the holes a³ through the slots a⁴. The 70 link E is then inserted in its place. The hook e' of link E engages with the bar a² when the pivot e is placed in the end of the hole a³, and the looped portion of the link can then be coupled to the pin of the coupling D in the 75 ordinary manner.

Having thus described my invention, what I claim as new, and desire to secure by Letters Patent, is—

1. In a car coupling, the combination of a 80 socket in the top of the draw-head, a removable coupling hook or link having lateral bearings and pivoted in the said socket, and a cover-plate pivoted to the top of the draw-head over said socket and retaining the said 85 hook or link within it, substantially as and for the purpose set forth.

2. In a car-coupling, the combination of the 90 socket A, provided with the holes a and a³, the slots a' and a⁴, and the bar a², a coupling hook or link pivoted in the said socket, and a cover-plate pivoted to the top of the said 95 socket and retaining the said hook or link within it, substantially as and for the purpose set forth.

3. In a car-coupling, the combination of the 100 socket A, provided with the holes a and a³, the slots a' and a⁴, and the bar a², the coupling-hook B, provided with the pivots b, the trip b', and the stop b², and the cover-plate C, provided with the pivot-pin c and slot c', substantially as and for the purpose set forth.

In testimony whereof I affix my signature in presence of two witnesses.

MATHEW DILL.
